UNITED STATES PATENT OFFICE.

WALTER D'A. RYAN, OF WATERTOWN, SOUTH DAKOTA, ASSIGNOR TO GENERAL ELECTRIC COMPANY, A CORPORATION OF NEW YORK.

DESIGN FOR A DIFFUSING-GLOBE FOR INCANDESCENT-LAMP CLUSTERS.

41,784.

Specification for Design.

Patented Sept. 19, 1911.

Application filed August 30, 1909. Serial No. 515,371. Term of patent 14 years.

To all whom it may concern:

Be it known that I, WALTER D'A. RYAN, a subject of the King of Great Britain, residing at Watertown, county of Codington, State of South Dakota, have invented a certain new, original, and ornamental Design for a Diffusing-Globe for Incandescent Lamp Clusters, of which the following is a specification, reference being had to the accompanying drawing, forming part thereof.

The drawing represents in Figure 1 a side elevation and in Fig. 2 a perspective view of a diffusing globe embodying my novel and ornamental design.

The globe is approximately circular in horizontal section, and somewhat resembles the calyx of a flower, being composed

of a number of semi-egg-shaped lobes all of the same size grouped in a circle and integrally connected at their edges, with downwardly-turned tips at their common central meeting point. Their upper edges are joined to a frusto-conical ring having a crown flange projecting upwardly from the outer edge thereof.

The globe is made of opal or frosted glass or other translucent material.

I claim:

The ornamental design for a diffusing globe for incandescent lamp clusters as shown and described.

WALTER D'A. RYAN.

Witnesses:

BENJAMIN B. HULL,
FRED KLAUMINZER.
